UNITED STATES PATENT OFFICE.

NICHOLAS D. SCARLING, OF RICHMOND, VIRGINIA.

WINDOW CLEANER.

Application filed August 31, 1921. Serial No. 497,271.

To all whom it may concern:

Be it known that NICHOLAS D. SCARLING, a citizen of the United States, residing at Richmond, in the county of Henrico and State of Virginia, has invented certain new and useful Improvements in Window Cleaners, of which the following is a specification.

This invention relates to new and useful improvements in window washing apparatus, and more particularly to a device of this character known as the fountain type wherein water is fed to the window directly from the apparatus, and the primary object 15 of the invention is to provide a device of this character which is of a combination type, providing the washing and the squeegee or drying portions in one.

Still another object of the invention resides in providing a device comprising a reservoir and a washing member in connection therewith which admits of the cleaning fluid to be readily fed to the window or surface over which the washing member is applied, and a still further object resides in providing a squeegee or water removing member which may be applied over said washing member, thus forming a combination device.

30 A still further object resides in providing a device which is simple and durable in construction, inexpensive to manufacture and one which will be very efficient and useful in operation.

35 With these and other objects in view, my invention consists in the novel features of construction, combination and arrangement of parts as will be hereinafter referred to and more particularly pointed out in the specification and claim.

40 In the accompanying drawing forming a part of this application—

Figure 1 is a perspective view of a device constructed in accordance with my invention, the squeegee member being shown removed from the washing member;

Figure 2 is a top plan view of the device with parts broken away and parts in section; and

50 Figure 3 is a reduced transverse section through the device as seen on the line 3—3 of Figure 1, with the handle member broken away.

In describing the invention I shall refer 55 to the drawing in which similar reference characters designate corresponding parts

throughout the several views, and in which 1 designates a substantially cylindrical reservoir having a neck or socket portion 2 formed thereon receptive of an elongated 60 handle 3. Water or other cleaning fluid may be supplied to the reservoir through an inlet 4, and formed on one side of the reservoir 1 is a channel-shaped chamber or the like 5. This chamber is adapted to receive 65 the washing member described herebelow.

The washing member comprises preferably a rectangular block 6 which is covered with an absorbent material such as felt or the like designated in the drawing as 7. 70 The felt covers the side, and end outer walls of the block, and is increased in thickness on the outer walls which constitutes the washing face of the device, and at predetermined points in the block 6 are provided a 75 plurality of channels 8. These channels register at their inner ends with openings 9 formed in the reservoir 1 at the base of the chamber 5 so that the cleaning fluid within the reservoir may feed through the channels 80 8 to the absorbent material 7. Thus it will be seen that after the reservoir is properly filled and the washing member applied in position within the chamber 5, the fluid will flow freely to the washing member and by 85 movement of the complete device over a window or other surface, the latter will be properly supplied with the cleaning fluid and washed.

As stated, my invention contemplates the 90 provision of a combination washing and squeegee apparatus, and to this end I provide a squeegee or water removing device which comprises a channel-shaped member 10 formed preferably of metal and adapted 95 to be readily applied over and to fit snugly against the walls of the chamber 5. The outer wall of the channel-shaped member 10 is provided with a pair of spaced apart and parallel flanges 11 between which is adapted 100 to be inserted a rubber strip 12. This rubber strip is secured between the flanges by means of screws 13 engaged at their ends with wing nuts 14.

It will thus be seen from this construction 105 that after the window or other surface has been washed by a movement of the washing device thereover, the squeegee is applied to the washing apparatus and the device then drawn over the window or other surface to remove the washing fluid therefrom. In 110 this manner it is only necessary for the op-

erator to first remove the squeegee from the washing device and when it is desired to use the squeegee, then to apply it in the same manner in which the device was used as a washing member. In this manner a combination device is formed, which will eliminate the necessity of carrying two separate and distinct members about personally by the operator, and will at the same time afford greater convenience and simplicity in operation. It will also be seen that the washing member may be quickly and readily removed from the device when desired, thus permitting of a new one to be supplied after the old one has become unduly worn.

From the foregoing description of my improved device, it will be seen that I have provided a simple, inexpensive and efficient means for carrying out the objects of the invention.

While I have particularly described the

elements best adapted to perform the functions set forth, it is obvious that various changes in form, proportion and in the minor details of construction may be resorted to without departing from the spirit or sacrificing any of the principles of the invention.

Having thus described my invention, what I claim is:

A cleaning appliance of the class described comprising a support, a handle therefor, an elongated cap detachably mounted on said support, parallel flanges upstanding from a wall of said cap, a rubber strip clamped between said flanges and extending beyond the free outer edges thereof, said clamping means passing through said parallel flanges and rubber strip.

In testimony whereof I affix my signature.

NICHOLAS D. SCARLING.
